UNITED STATES PATENT OFFICE.

STURGIS C. RICE, OF FRANKLIN, MASSACHUSETTS, ASSIGNOR TO WHITING & DAVIS COMPANY, OF PLAINVILLE, MASSACHUSETTS, A CORPORATION OF MASSACHUSETTS.

DESIGN FOR A METAL MESH FABRIC.

Application filed March 2, 1928. Serial No. 25,649. Term of patent 14 years.

To all whom it may concern:

Be it known that I, STURGIS C. RICE, a citizen of the United States, residing at Franklin, Norfolk County, Massachusetts, have invented a new, original, and ornamental Design for Metal Mesh Fabric, of which the following is a specification, reference being had to the accompanying drawing, forming part thereof.

Fig. 1 is a plan view of a section of metal mesh fabric showing my new design.

Fig. 2 is a cross-sectional view of one of the links of the metal mesh fabric connected to the adjacent rings.

I claim:

The ornamental design for metal mesh fabric as shown.
